(57) **CLAIM**

The ornamental design for a training device, as shown and described.

DESCRIPTION

2. Training device

Fig. 2.1 is a perspective view of the training device in an extended configuration;

Fig. 2.2 is a perspective view of the training device in a folded configuration;

Fig. 2.3 is a front view of the training device in an extended configuration;

Fig. 2.4 is a front view of the training device in a folded configuration;

Fig. 2.5 is a back view of the training device in an extended configuration;

Fig. 2.6 is a back view of the training device in a folded configuration;

Fig. 2.7 is a left view of the training device in an extended configuration;

Fig. 2.8 is a left view of the training device in a folded configuration;

Fig. 2.9 is a right view of the training device in an extended configuration;

Fig. 2.10 is a right view of the training device in a folded configuration;

Fig. 2.11 is a top view of the training device in an extended configuration;

Fig. 2.12 is a top view of the training device in a folded configuration;

Fig. 2.13 is a bottom view of the training device in an extended configuration;

Fig. 2.14 is a bottom view of the training device in a folded configuration.
